CLAIM

We claim the ornamental design for a infusion pump cassette, as shown.

DESCRIPTION

FIG. 1 is an exploded assembly view of a infusion pump cassette according to the invention.

FIG. 2 is a rear corner perspective view of the cover of a infusion pump cassette according to the invention, the cover being shown separately for clarity of illustration.

FIG. 3 is a front elevational view of the cover of a infusion pump cassette according to the invention.

FIG. 4 is a rear elevational view of the cover of a infusion pump cassette according to the invention.

FIG. 5 is a top plan view of the cover of a infusion pump cassette according to the invention.

FIG. 6 is a bottom plan view of the cover of a infusion pump cassette according to the invention.

FIG. 7 is a right side elevational view of the cover of a infusion pump cassette according to the invention.

FIG. 8 is a left side elevational view of the cover of a infusion pump cassette according to the invention.

FIG. 9 is a front corner perspective view of the rear housing of a infusion pump cassette according to the invention, the housing being shown separately for clarity of illustration.

FIG. 10 is a front elevational view of the rare housing of a infusion pump cassette according to the invention.

FIG. 11 is a rear elevational view of the rear housing of a infusion pump cassette according to the invention.

FIG. 12 is a top plan view of the rear housing of a infusion pump cassette according to the invention.

FIG. 13 is a bottom plan view of the rear housing of a infusion pump cassette according to the invention.

FIG. 14 is a right side elevational view of a infusion pump cassette according to the invention; and,

FIG. 15 is a left side elevational view of a infusion pump cassette according to the invention.
